UNITED STATES PATENT OFFICE.

FRANK M. WOODS, OF YORK, ASSIGNOR OF ONE-HALF OF HIS RIGHT TO
JOHN MORTON, OF MARSHALL, ILLINOIS.

PRESSER-FOOT AND GUIDE FOR SCROLL-SAWS.

SPECIFICATION forming part of Letters Patent No. 233,059, dated October 5, 1880.

Application filed July 10, 1880. (No model.)

To all whom it may concern:

Be it known that I, FRANK M. WOODS, of York, in the county of Clark and State of Illinois, have invented certain new and useful 5 Improvements in Presser-Feet and Guides for Scroll-Saws; and I do hereby declare the following to be a full, clear, and exact description of the invention, such as will enable others skilled in the art to which it pertains to 10 make and use it, reference being had to the accompanying drawings, which form part of this specification.

My invention relates to an improvement in scroll-sawing machines; and it consists in the 15 adjustable slotted parts which form the arm for supporting the guide and presser-foot, as will be more fully described hereinafter.

The object of my invention is to provide a scroll-sawing machine in which only a single 20 end of the saw is attached to any device, and having the guide at the same time act as a presser-foot, and to regulate the pressure of this foot upon the material being sawed by the arm which supports it.

25 Figure 1 is a side elevation of my invention. Fig. 2 is an end view of the same. Fig. 3 is a detail view.

A represents the frame of the machine, upon the top of which the table B is secured. Pivoted in the lower part of this frame is the treadle C, which has one end connected to the driving-wheel D by means of the connecting-rod E. From this driving-wheel passes the belt F, which operates the wheel G on the 35 shaft H, which shaft has a balance-wheel, I, secured to its other end. This wheel G is provided with a wrist-pin, to which is fastened a connecting-rod, J, which has its lower end fastened to the vertically-moving rod L. To 40 the upper end of this rod L the lower end of the saw is rigidly clamped by means of any suitable device. This saw extends up through the table, but instead of having its upper end attached to an arm, spring, or a guide of some 45 kind, the end is left entirely free, so that it plays loosely up and down in the groove O,

which is made in the combined guide and presser-foot N.

By not connecting the upper end of this saw to any other device I find that the saw operates just as well, is not so liable to be broken, and is much more easily attached to the machine, at the same time that the friction is correspondingly reduced. This guide having a slot in its edge for the saw to work in, serves 55 also as a presser-foot to hold down the material upon which the saw is operating, and has a vertical slot, P, made through it, so that it can be adjusted up and down to suit the different thicknesses of material being 60 sawed. This combined presser-foot and guide is clamped to the front end of the arm which supports it, and this arm is composed of the two slotted horizontal pieces R and the curved piece S. By means of the slots in the two 65 pieces R the length of the arm can be increased or decreased at will, and thus augment or diminish the pressure of the foot upon the material.

By making the curved part S elastic the 70 pressure of the presser-foot can be regulated at will. By extending the arm by means of the slots a greater sweep is given to the arm and a finer adjustability to the presser-foot.

Having thus described my invention, I 75 claim—

In a scroll-sawing machine, the combination of the two supporting-arms R, an intermediate elastic connecting-arm, S, and a presser-foot, N, fastened to the free end of the upper 80 one of the arms R, the arm S being made adjustable back and forth on the arms, so as to increase or decrease the pressure of the foot by lengthening or shortening the leverage, substantially as set forth. 85

In testimony that I claim the foregoing I have hereunto set my hand this 23d day of June, 1880.

FRANK M. WOODS.
